UNITED STATES PATENT OFFICE.

CLYDE A. HALL, OF POTTSVILLE, PENNSYLVANIA.

LIGHTER.

Application filed June 19, 1924. Serial No. 721,100.

To all whom it may concern:

Be it known that I, CLYDE A. HALL, a citizen of the United States, residing at Pottsville, in the county of Schuylkill and

5 State of Pennsylvania, have invented certain new and useful Improvements in Lighters, of which the following is a specification.

This invention relates to devices for facilitating the lighting of cigars and cigarettes.

10 The object of the invention is to provide a compact container and novel mechanism therein whereby an inflammable pellet may be fed to a flame pocket which is accessible to admit a cigar or cigarette which is to be

15 lighted, the pellet being ignited during its passage to the flame pocket. The invention also provides novel means for feeding the pellets singly to the flame pocket, and novel means for igniting the pellet immediately

20 prior to its entrance into the flame pocket. The invention is illustrated in the accompanying drawing and will be hereinafter fully set forth.

The drawing is a view, partly in side elevation and partly in vertical section, of a device embodying the invention.

In carrying out the invention, I employ a container 1 which may be of any suitable material and will preferably be of such dimensions that it may be conveniently held in the hands of the user. The container is provided with an open top normally closed by a hinged cover 2, and within the container is a tapered bottom 3 whereby the

35 pellets, indicated at 4, are fed to an outlet 5. Below the tapered bottom 3 is a tubular guide 6 in which is mounted a plunger 7 and into which the port 5 opens. The tubular guide 6 and the webs defining the outlet port 5 may be formed integral with the tapered bottom 3 and the front wall 8 of the container near its lower end is carried inwardly and downwardly, as shown at 9, to merge into the top wall of the tubular

40 guide and constitute the top of the flame chamber, indicated at 10. The port 5 is of such dimensions that it will permit the passage of only one pellet at a time and the pellet will be received upon the bottom wall of the tubular guide 6 immediately in front of the plunger 7, as shown in the drawing. A concave web 11 forms the bottom of the flame chamber and forms a connection between the bottom wall of the

50 tubular guide and the front wall of the container, the said front wall being uninter-

rupted to provide an opening through which access may be had to the flame chamber. It will also be readily noted that the concave web or wall 11 serves as a cup into which the ignited pellet will fall and by which it will be prevented from rolling from the container. An expansion spring 12 is housed within the guide 6 between the inner end of the plunger 7 and a plug 13 which is fitted in the rear or outer end of the guide the said spring tending constantly to move the plunger to the front end of the guide so that it will cut off the passage of pellets through the port 5, as will be readily understood. A lever 14 is fulcrumed upon a side or end wall of the container and has its lower end pivotally connected with the plunger, while its upper end is provided with a laterally extending handle member 15 playing in an arcuate slot 16 in the wall of the container whereby the lever may be manipulated to expel a pellet. The bottom 3 and the upper wall of the guide 6 are provided with slots to accommodate the lever, as shown at 17 and 18 and will be understood readily.

At the front end of the guide 6 and in the upper wall of the same is an ignition member 19 which may be of any approved construction and is adapted to project through the wall of the guide so as to present a roughened surface, indicated at 20, to a pellet fed below it. This ignition block is provided with a shoulder 21 whereby it is prevented from dropping through the upper wall of the tubular guide and it is yieldably held to said wall by a spring 22 disposed between the block and an abutment 23 upon the tapered bottom 3. A similar ignition block 24 is provided below the guide and carries an abrading face 25 which is adapted to project through the bottom wall of the guide immediately below the abrading member 20 so as to cooperate therewith, a spring 26 being provided to yieldably support the block 24, as shown. It will be noted that the opposed abrading faces converge toward the flame pocket and, therefore, readily admit a pellet between them but will bear frictionally against the same with increasing tension as the pellet is fed to the flame pocket so that ignition of the pellet will be positively effected.

The drawing represents the several parts in the position assumed immediately prior to the feeding of a pellet to the flame cham-

ber. The expansion of the spring 12 will cause the plunger to move forwardly and the lever will then assume the position shown in dotted lines, the rocking of the lever being limited by the impact of the handle member 15 against the rear end of the slot 16. As the pellet deposited in front of the plunger is forced between and past the abrading faces, the friction thereby generated will ignite the pellet so that it will drop into the flame poéket while burning. The end of the cigar or cigarette to be lighted may be easily inserted through the open front side of the flame pocket so as to permit the flame to play thereon and it will be easily and quickly lighted. When it is again desired to use the device, the handle member 15 is swung forwardly and then released, thereby rocking the lever so that the plunger 7 will be withdrawn and a second pellet may leave the port 5 and be deposited in front of the plunger. The dropping of the pellet will occur simultaneously with the arrival of the plunger at its innermost position and when the handle 15 is released the immediate expansion of the spring 12 will force the plunger forward and cause the pellet to pass between the abrading faces, as before described.

My device is exceedingly simple and compact and may be produced at a low cost. It may be easily manipulated and will operate positively to produce a flame in the flame pocket which will burn long enough to permit a cigar or cigarette to be easily lighted. The pellets may, of course, be of any form and may have a wooden central core if desired.

Having thus described the invention, what is claimed as new is:

A device for the purpose set forth comprising a container having a tapered bottom and adapted to hold combustible pellets, a port leading from the said tapered bottom to permit the escape of a single pellet, a guide disposed below the tapered bottom and in communication with said port, a flame pocket at the front end of said guide and in communication therewith, opposed yieldably mounted igniting members arranged in the guide immediately adjacent the flame pocket, a plunger reciprocable in said guide and adapted to feed a pellet past the igniting members into the flame pocket, yieldable means for normally holding the plunger projected, and means for retracting the plunger.

In testimony whereof I affix my signature.
CLYDE A. HALL. [L. s.]
